US00D758180S

(12) **United States Design Patent**
Wintmolders et al.

(10) **Patent No.:** US D758,180 S
(45) **Date of Patent:** ** Jun. 7, 2016

(54) **CONTAINER**

- (71) Applicant: **The Procter & Gamble Company**, Cincinnati, OH (US)
- (72) Inventors: **Wim Wintmolders**, West Chester, OH (US); **Rainer Bernhard Teufel**, Worthington, OH (US); **Igor Ivanovich Zemskov**, Dublin, OH (US); **David William Schuller**, Lebanon, OH (US)
- (73) Assignee: **The Procter & Gamble Company**, Cincinnati, OH (US)
- (**) Term: **15 Years**
- (21) Appl. No.: **29/542,262**
- (22) Filed: **Oct. 13, 2015**

(57) **CLAIM**

The ornamental design for a container, as shown and described.

DESCRIPTION

FIG. 1 is a perspective view of a container showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan thereof; and,

FIG. 7 is a bottom plan view thereof.

The broken lines depict portions of the container in which the design is embodied that form no part of the claimed design.

1 Claim, 6 Drawing Sheets
